UNITED STATES PATENT OFFICE.

FRANK E. WOOD AND CLARENCE G. WOOD, OF GIRARD, PENNSYLVANIA, ASSIGNEES
TO GIRARD MODEL WORKS, INC., OF GIRARD, PENNSYLVANIA.

TOY AEROPLANE.

Application filed January 7, 1921. Serial No. 435,590.

To all whom it may concern:

Be it known that we, FRANK E. Wood and CLARENCE G. Wood, citizens of the United States, residing at Girard, in the county of Erie and State of Pennsylvania, have invented new and useful Improvements in Toy Aeroplanes, of which the following is a specification.

This invention has to do particularly with 10 the construction of the toy both in relation to simplifying its manufacture and adding to its strength and convenience of operation and also to its attractiveness as to appearance.

15 The invention is illustrated in the accompanying drawings as follows:—

Fig. 1 shows a side elevation of the toy.

Fig. 2 a front elevation.

Fig. 3 a section on the line 3—3 in Fig. 2.

20 Fig. 4 a bottom view of the toy.

Fig. 5 a bottom view of a part of the fuselage.

Fig. 6 a bottom view of the rear end of the fuselage.

25 1. marks the fuselage. This is arched and open at the bottom. It has the projections 2. The wheels 3 are mounted on an axle 4 extending through the walls or projections 2.

The wheels are driven directly from a 30 motor formed as follows:—A shaft 5 extends from wall to wall of the fuselage and is provided with a winding handle 6. A ratchet wheel 7 is fixed on this shaft. A pawl 8 operates on the ratchet wheel, the pawl being 35 in the form of a spring secured by the ears 9 and 10 on the side of the frame. A perforated ear 11 is formed on the ratchet wheel 7 and a spring 12 is secured to this ear 11. A spring 12 is formed on a barrel 13, the

40 opposite end of the spring from the ear 11 being secured to this barrel. A gear 14 is fixed on the barrel. It meshes with a pinion 15. The pinion 15 is fixed on the shaft 16 journaled in the walls of the fuselage. A gear 17 is fixed on the gear 15 and meshes 45 with a pinion 18 on the axle 4. It will readily be seen that as the spring is wound through the key or handle 6 that the unwinding of the spring operating through the

50 gearing mentioned on the axle will turn the wheels 3.

A grooved pulley 20 is mounted on the axle and a small belt in the form of a rubber band extends from this pulley to a pulley 22

55 on a propeller shaft 23. A propeller 24 is

fixed on the front end of the shaft 23. A radiator 25 is mounted on the front end of the fuselage. It has a perforation 26 at the top through which a tongue 27 on a securing plate 28 extends. The plate 28 is secured to the top of the fuselage and has a downward bend 29 at its rear end which forms a hanger for a bearing for the rear end of the propeller shaft.

The fuselage is severed at 31 from the 60 front end to the opening 30 and is drawn together thus shaping the front end of the fuselage and narrowing it to add to its appearance. The plate 28 is secured at each side of this line of severance by the tongues 65 and slots 32 and 33. The wing plate 34 has the tongues 35 at its front end which extend through slots 36 at the top of the fuselage. The wing plate is notched so as to extend each side of the opening 30 and has the 70 tongues 35^a extending through grooves 36^a in the fuselage. The top of the arch has a downward projection 37 formed with the metal which is cut out in forming the opening 30 on which a figure 38 is mounted.

The rear end of the fuselage has the projections 39 at the lower end of the arched wall and these projections are bent in overlapping each other. A rudder post 40 extends through the top or wall of the frame 85 and through a slot 41 in the projections 39. A rudder 43 has a slot 44 leaving a portion at the bottom and top of the horizontal rudder 47. The top and bottom of the rudder 43 above and below the slot are bent at 45 and 46 around the rudder post. The horizontal rudder 47 has notches 48 along its edge which are engaged by the vertical rudder. A spring 49 operating on the rudder post yieldingly holds the vertical rudder in 90 engagement with the horizontal rudder 47 so that the vertical rudder may be swung from side to side and yieldingly locked in position. A downward projection 50 is formed on the vertical rudder 43 and a companion leg 51 is bent over the lower portion of the vertical rudder at 52. A wheel 53 is mounted on an axle 54 which extends between the projection 50 and the leg 51. It will readily be seen that as the vertical rudder 95 is swung the wheel 53 is swung with it so that the device may be made to run in a circle if desired.

What is claimed as new is:—

1. In a toy aeroplane, the combination of 110

1. a fuselage of arched form; a plane secured to the upper part of the arch; an axle journaled in the walls of the arch; a motor within the arch and housed thereby; and 5 a gear connection between the motor and the axle.
2. In a toy aeroplane, the combination of a fuselage of arched form; a plane secured to the upper part of the arch; an axle 10 journaled in the walls of the arch; a motor within the arch and housed thereby; and a gear connection between the motor and the axle, the shafts of the motor extending from wall to wall of the arch.
- 15 3. In a toy aeroplane, the combination of a fuselage of arched form split along the top from the front and drawn together; a radiator on the front; a propeller shaft extending through the radiator; and a locking 20 plate securing the radiator and covering the line of severance along the top of the fuselage and having its rear end bent downwardly forming a hanger for the rear end of the propeller shaft.
- 25 4. In a toy aeroplane, the combination of a fuselage of arched form having an opening at the top for a figure; a wing plate secured at the top of the fuselage by a tongue and slot connection, the plate being 30 notched at the opening of the fuselage and the plate at the sides of the notch being bent downwardly extending along the sides of the fuselage; and a tongue and slot connection between the wing plate and the 35 sides of the fuselage.
5. In a toy aeroplane the combination of a fuselage; a vertical rudder pivotally mounted and adjustable on the fuselage at its rear end; a wheel carried by the rudder 40 and in alinement therewith; and means for yieldingly locking the rudder in adjustment on the fuselage.
- 45 6. In a toy aeroplane, the combination of a fuselage of arched form; a rudder post extending through the top of the arch; projections from the bottom of the wall of the arch forming a bearing for the bottom of the rudder post; and a rudder pivotally mounted on the post, said rudder being secured to the post above and below the top 50 wall of the arch.
7. In a toy aeroplane, the combination of a fuselage having arched form; a rudder post extending through the top of the arch; projections from the bottom of the wall of the arch forming a bearing for the bottom of the rudder post; a rudder pivotally mounted on the post, said rudder being secured to the post above and below the top 55 wall of the arch; and a horizontal rudder 60 extending from the fuselage and yieldingly engaging the first named rudder.
8. In a toy aeroplane, the combination of an arch shaped fuselage; a rudder post extending through the fuselage; projections forming a bearing for the bottom of the post, said projections having a slot through which the post extends; a spring yieldingly holding the post at one end of the slot; a vertical rudder mounted on the post; and 65 a horizontal rudder having notches engaging the vertical rudder, the spring permitting the yielding of the vertical rudder to permit its movement along the horizontal rudder. 75
9. In a toy aeroplane, the combination of a fuselage; a vertical rudder pivotally mounted on the fuselage at its rear, said rudder having a downward projection forming a leg; a second leg secured to the rudder; a wheel mounted between the legs and in alinement with the rudder; and an axle 80 on which the wheel is mounted extending between the legs.
- In testimony whereof we have hereunto 85 set our hands.

FRANK E. WOOD,
CLARENCE G. WOOD.
